UNITED STATES PATENT OFFICE.

BENJAMIN H. HYSON, JR., OF SALEM, NEW JERSEY.

DESIGN FOR A STAIR TREAD.

Application filed September 17, 1928. Serial No. 28,175. Term of patent 3½ years.

To all whom it may concern:

Be it known that I, BENJAMIN H. HYSON, Jr., a citizen of the United States, residing at Salem, in the county of Salem and State of New Jersey, have invented a new, original, and ornamental Design for Stair Tread, of which the following is a specification, reference being had to the accompanying drawing, forming part thereof, and in which—

Fig. 1, is a face view of a stair tread showing my new design; and

Fig. 2, is an edge view thereof.

The detailed illustration of the design shown at the upper half of the stair tread is repeated at the lower half.

I claim:

The ornamental design for a stair tread as shown and described.

BENJAMIN H. HYSON, JR.
